UNITED STATES PATENT OFFICE.

FREDERICK J. KIENEL AND WALTER M. SCHWARTZ, OF PHILADELPHIA, PENNSYLVANIA, ASSIGNORS TO PROCTOR & SCHWARTZ, INCORPORATED, OF PHILADELPHIA, PENNSYLVANIA, A CORPORATION OF PENNSYLVANIA.

METHOD OF FINISHING HOSIERY.

Application filed October 18, 1921. Serial No. 508,488.

To all whom it may concern:

Be it known that we, FREDERICK J. KIENEL and WALTER M. SCHWARTZ, citizens of the United States, residing in Philadelphia, Pennsylvania, have invented certain Improvements in a Method of Finishing Hosiery, of which the following is a specification.

Our invention relates to certain improvements in the process of finishing hosiery.

One object of our invention is to apply the hosiery to the forms more rapidly than heretofore and to moisten the hosiery while on the forms prior to the final drying and shaping of the hosiery.

A further object of the invention is to straighten the hosiery on the form after the form, with the hosiery thereon, has passed through the moistening chamber and prior to its passage into the drying chamber.

These objects we attain in the following manner, reference being had to the accompanying drawings, in which:

Fig. 1 is a plan view in diagram showing a stocking drying machine equipped to dry hosiery in accordance with our invention; and

Fig. 2 is a sectional view on the line 2—2, Fig. 1.

While our invention can be carried out by hand, or by any well known stocking drying machine, the machine illustrated is of the type illustrated and claimed in the patent granted to Harry Coulston and Walter M.

Schwartz, No. 1,126,619, January 26, 1915.

Referring to the drawing, 1 is the frame of the machine. 2 is the drying chamber. 3 are guideways for the stocking boards 4, which are traversed in a rectangular path 40 in front of the drying chamber and then through the drying chamber. At the front of the machine is a moistening chamber, or box, 5 through which pass the forms with the stockings thereon. This chamber can be of any length desired and the moisture can be regulated by any well known means.

In the present instance, a steam pipe 8 is shown exhausting into the moistening chamber, but any means may be used for supplying moisture.

The stockings are placed upon the forms in a dry condition at the point *a* and the forms, with the stockings thereon, pass into the moistening chamber 5, where they are moistened. The stockings, when moistened 55 to the proper degree, pass out of the moistening box and a second operator at the point *b* straightens the stockings on the forms. The stocking forms, with the stockings thereon, pass into the drying chamber 2. 60 The stockings are subjected to hot air in circulation while in the chamber, suitable steam coils 6 being provided to heat the air to the proper degree and a circulating fan 7, driven in any suitable manner, circulates the air 65 in the drying chamber.

When the forms, with the dried stockings thereon, emerge from the drying chamber, the stockings can be removed by hand, or by automatic mechanism illustrated in the patent hereinbefore alluded to, or by other suitable devices for accomplishing this purpose.

By our invention, the stockings can be placed on forms in a dry condition. This can be accomplished much more readily than 75 when the stockings are damp. By passing the forms, with the stockings thereon, through a moistening chamber, the amount of moisture can be regulated so that the stockings will be properly moistened, after 80 which the stockings can be straightened on the forms before being finally dried and shaped.

We claim:

The method herein described of finishing 85 stockings, said method consisting in placing the stockings on forms while in a dry condition; passing the stockings while on the forms through a moistening chamber in which they will receive the proper degree of 90 moisture; straightening the stockings while on the forms after they leave the moistening chamber; and then passing the stockings while on the forms through a drying chamber in which the heated air is circulated in 95 direct contact with the stockings.

FREDERICK J. KIENEL.
WALTER M. SCHWARTZ.
